UNITED STATES PATENT OFFICE

AUGUSTE HARER, OF VIENNE LE CHATEAU, FRANCE

CIRCULAR KNITTING MACHINE

Application filed October 27, 1930, Serial No. 481,628, and in Belgium November 16, 1929.

The present invention relates to circular knitting machines.

One of the objects of the invention is to improve circular machines so that openwork (eyelet) designs of any desired configuration may be knitted thereon.

Other objects will appear in the course of the detailed description now to be given with reference to the accompanying drawings, in which.

Figs. 1 to 6 show various stages in an openwork knitting operation;

Fig. 7 is an elevation of the retaining element for holding back threads;

Fig. 8 represents, diagrammatically, means for actuating one or a series of retaining elements.

Fig. 9 shows the cam control for the various retaining elements.

Referring to Figs. 1 to 6 of the drawings, there is shown a series of phases in the knitting of a fabric including openwork or eyelets on a circular machine. A thread or threads c, c^1, c^2, c^3 are successively supported by needles of the type d^1, d^2 to form rows of convex and concave loops a, a^1, a^2, a^3 and b^1, b^2 etc. Assuming a pair of convex loops b^1, b^2 to be supported on needles d^1, d^2 , before thread is supplied from a convenient source to said needles, a retaining element or transfer point provided with a laterally inclined hooking portion f moves into position between d^1 and d^2 so that the thread coming from the source lies in f while the circular machine rotates. The desired number of loops having been retained during a number of revolutions of the machine, the transfer point advances (Fig. 5) until an opening therein h^0 is positioned over one of the needles e. g. d^1 . Needle d^1 then rises and, before contacting with thread e , enters opening h^0 under retained loops a^1, a^2, a^3 . Transfer point f then withdraws and needle d^1 passes the ensemble of threads carried thereby above thread e to form a loop (Fig. 6) connected to the one preceding by the combined threads indicated.

In order to carry out the above operations and, more especially, in order to withdraw transfer point f after it has taken up its posi-

tion over needle d^1 , opening h^0 is formed between a pair of flexible elements h^1 and h^2 , the flexibility of the latter permitting laterally inclined portion f to slide over needle d^1 .

The transfer points are mounted on a plate 55 positioned near the top of the needle cylinder (i. e. adjacent the position where the needles reciprocate vertically) and move radially in recesses formed in the plate under the action of cams driven by the mechanism 60 actuating the knitting. The plate in question is formed with as many recesses as there are needles so that, by introducing transfer points at suitable intervals, any desired open 65 work design may be knitted.

The various cams contact with stems i (Fig. 7) integral with the transfer points. Three cams are used: the first k^1 (Fig. 9) advances the transfer point until hook f takes up a position between two needles d^1 and d^2 ; a second cam k^2 then advances the transfer point until opening h^0 is just above needle d^1 ; finally cam k^3 retracts the transfer point. Cam k^1 , supported on element l^1 , and cams k^2, k^3 supported on element l^2 , may be moved 70 into, and out of, action by displacing elements l^1 and l^2 towards, or away from stems i .

In the prior art devices, stems i were of equal length, so that the openwork design was limited to a series of parallel lines of equal length. In accordance with the present invention, they are grouped in series in which stems of different height are used. The cams will, therefore, displace only certain stems (transfer points) while leaving the remainder at rest. For example, if it be desired to produce a knitted article which presents, successively, series of rows of loops traversed by one eyelet then three, then five, then three, and finally one, an assembly of the type shown in Fig. 7 should be employed.

For the single eyelets, a transfer point having a stem height i^3 is used; for three eyelets, stem height i^2 (less than i^3) is used; for five eyelets, use is made of i^1 , lower than both i^3 and i^2 . Transfer points of stem height i , though not necessary for forming a fabric such as described, may be distributed near the beginning portion of the needle cylinder so 100

as to cooperate with transfer points i^1 , i^2 , i^3 to form the design desired.

The supports for cams k^1 , k^2 and k^3 should then be adjusted so that said cams contact first with stems i , then successively, with stems i^3 , i^2 and i^1 . The arrangement shown in Fig. 8 illustrates how this may be accomplished. Naturally, if designs formed otherwise are desired, the adjustment of the cams 10 the number of transfer points and the height of their stems may be varied at will. In the description that follows, only the mechanism lowering cam k^1 , i. e. for advancing the transfer points, will be described. Once the 15 transfer point has been displaced by k^1 , it remains at rest during as many turns of the machine as desired e. g. three turns, when three loops are to be retained. Cams k^2 and k^3 are mounted on a common support l^2 , because the movements effected thereby follow 20 one another closely. Support l^2 may be controlled in a manner similar to support l^1 , supporting cam k^1 and the actuating mechanism for its cams, may be similar to that 25 for cam k^1 .

Support l^1 is made in the form of a lever oscillating about fixed axis m . A rod n suspended at one end of lever l^1 is positioned so that its free extremity contacts periodically 30 with a lever o keyed to the shaft of a ratchet wheel o^1 actuated through an angle corresponding to a predetermined number of teeth by an oscillatable dog p supported on the end of a lever q articulating at q^1 with a 35 pair of pivotally connected elements r^1 , r^2 . A lever s capable of oscillating about an axis t is connected to element r^2 and is provided, at one end, with a roller u contacting with a cam v rotatably mounted at w . Cam v is 40 provided with a recessed portion v^1 positioned so that when roller u rides over the latter, lever s oscillates, raises r^1 and r^2 together, and moves lever q towards the right (Fig. 8). Dog p , thereupon, rotates wheel 45 o^1 through an angle corresponding, let us say, to two teeth, moving levers o and n upward, and lowering cam k^1 . Cam v may be driven from the knitting machine motor by an automatic clutch (not shown) of any desired current design controlled by hand or by 50 a stop mounted on the chain generally used for stopping, starting and controlling circular machines.

The above described assembly would suffice if cam k^1 were to be moved downward to a predetermined level, but since the downward movements must be effected to different levels, the following auxiliary structure becomes necessary. Axis t , instead of being fixed, is mounted to slide in a guideway s^0 formed in lever s . Obviously, with different positions of axis t , ratchet wheel o^1 will rotate through different angles. Axis t is, therefore, 60 mounted on a bracket x , slidably guided at

one end in a guideway x^1 , bracket x being displaced by a step-profiled cam y reacting thereon against the action of a spring x^2 . Cam y is rotatably mounted on a longitudinally displaceable shaft z and may be displaced therewith by hand or otherwise, so as to bring either step y^1 or step y^2 into engagement with x , whereby either small (case of contact with y^1) or large (case of contact with y^2) downward displacements of cam k^1 be obtained. If an automatic displacement of shaft z be desired, it suffices to mount properly profiled cams (not shown) driven by the machine so as to react thereon.

What I claim is:

1. In a circular knitting machine, a needle positioned along the circumference of a circle, a transfer point, means for displacing said transfer point including a cam, a rotatable element operative to actuate said cam and means for rotating said rotatable element comprising a lever, a link having a slot formed therein, means slidably guided in said slot, a first cam operative to displace one end of said link, and a second cam operative to 80 displace said means.

2. A structure as defined in claim 1 in combination with a cam rigidly connected to said first named cam and positioned to be actuated by said first named means.

3. A structure as defined in claim 1 in combination with cam means operative to retract said transfer point, and means independent of said first named means positioned to 95 actuate said cam means.

4. A structure as defined in claim 1 in combination with cam means operative to retract said transfer point, and means for actuating said cam means including a cam, a rotatable element operative to actuate said last named cam and means for rotating said rotatable element, comprising a lever, a link having a slot formed therein, means slidably guided in said last named slot, and a cam operative to 100 displace one end of last named link.

5. In a circular knitting machine, a needle positioned along the circumference of a circle, a transfer point, and means for displacing said transfer point including a cam, a rotatable element operative to actuate said cam and means for rotating said rotatable element comprising a lever, a link having a slot formed therein, means slidably guided in said slot, a first cam operative to displace one end of said link, and a second cam having its 110 axis of rotation positioned at right angles to that of said last named cam, said second cam being operative to displace said last named means.

6. A structure as defined in claim 5 in combination with a spring acting on said last named means and opposing the action of said second cam.

In testimony whereof I affix my signature.

AUGUSTE HARER.
